UNITED STATES PATENT OFFICE

111,546

DESIGN FOR A COMBINED BOTTLE DISPLAY GROUP AND CONTAINER THEREFOR

Leo Mann, Providence, R. I.

Application November 4, 1937, Serial No. 72,620

Term of patent 7 years

To all whom it may concern:

Be it known that I, Leo Mann, a citizen of the United States, residing at Providence, in the county of Providence and State of Rhode Island, have invented a new, original, and ornamental Design for a Combined Bottle Display Group and Container Therefor, of which the following is a specification, reference being had to the accompanying drawing, forming part thereof.

Figure 1 is a perspective of a combined bottle display group and container therefor embodying my new design;

Figure 2 is a side view of the same; and Figure 3 is a side view, showing the cover of the container in section as on line 3—3 of Figure 1, removed from the base.

I claim:

The ornamental design for a combined bottle display group and container therefor, substantially as shown or described.

LEO MANN.
